(57) **CLAIM**

I claim the ornamental design for a boot, as shown.

DESCRIPTION

FIG. 1 is a front elevational view of the boot;

FIG. 2 is a top plan view of the boot of FIG. 1;

FIG. 3 is a back elevational view of the boot of FIG. 1;

FIG. 4 is a medial side elevational view of the boot of FIG. 1;

FIG. 5 is a bottom plan view of the boot of FIG. 1; and,

FIG. 6 is a lateral side elevational view of the boot of FIG. 1. The broken line showing of the stitching and sole in the drawings represents unclaimed environmental subject matter and forms no part of the claim.
